UNITED STATES PATENT OFFICE.

WORLEY N. CRISS, OF KITTANNING, PENNSYLVANIA.

PASSENGER'S TRAIN TICKET HOLDER.

1,404,192.

Specification of Letters Patent. Patented Jan. 24, 1922.

Application filed September 9, 1921. Serial No. 499,362.

To all whom it may concern:

Be it known that I, WORLEY N. CRISS, a citizen of the United States, residing at Kittanning, in the county of Armstrong and State of Pennsylvania, have invented certain new and useful Improvements in a Passenger's Train Ticket Holder, of which the following is a specification.

This invention relates to a ticket holder and has for its object to provide a device of this nature which is particularly simple in construction and highly efficient in use and it consists in the combination and construction hereinafter set forth and claimed.

15 In the drawing:—

Figure 1 is a perspective view showing the upper portion of a seat with the ticket holder attached thereto,

Figure 2 is a longitudinal vertical section 20 taken therethrough,

Figure 3 is a top plan of the ticket holder, and

Figure 4 is a transverse section therethrough.

25 Referring to the drawings by numerals it will be seen that 1 designates the back of a seat preferably those kind which are found in railroad coaches and this seat back 1 is provided with a recess 2 as shown to advantage in Figure 2. The ticket holder consists of a plate 3 forming a base and auxiliary plate 4 which is pressed therefrom so as to be integral therewith having its ends curved as shown at 5 whereas its body portion

35 extends in a plane parallel to the plane of the base plate 3. Apertured ears 6 are cut from the end portions of the auxiliary plate 4 and bent downwardly at right angles to the base plate 3 and form journals

for the shaft 7 upon which is mounted the 40 roller 8. This roller 8 is provided with a sheeting around its periphery as indicated at 9 preferably of some such material as rubber so as to grasp the ticket 10 when it is positioned as shown in Figure 1. 45

Having thus described my invention what I claim as new is:—

1. A ticket holder of the class described comprising a base plate, an auxiliary plate formed integral therewith so as to register 50 with a slot in the base plate, journal elements mounted on the base plate adjacent the slot and a roller mounted in said journal elements so as to register with said slot.

2. A device of the class described includ- 55 ing a base plate, an auxiliary plate, said base plate being provided with a slot, said auxiliary plate registering with said slot and in a plane spaced and parallel to the plane of the base plate, apertured ears projecting 60 downwardly from the base plate and a roller journaled in said ears.

3. As a new article of manufacture, a ticket holder comprising a base plate having an auxiliary plate pressed from its central portion so as to be spaced therefrom and extend in a plane parallel thereto, a pair of depending ears struck from the base plate and the ends of the auxiliary plate and ex- 65 tending at right angles from the base plate 70 and a roller journaled therein.

In testimony whereof I affix my signature in presence of two witnesses.

WORLEY N. CRISS.
